United States Patent Office.

C. W. GAGE, OF HOMER, NEW YORK.

Letters Patent No. 76,820, dated April 7, 1868.

IMPROVEMENT IN FRUIT-GATHERERS.

The Schedule referred to in these Letters Patent and making part of the same.

TO ALL WHOM IT MAY CONCERN:

Be it known that I, C. W. GAGE, of Homer, in the county of Cortland, and State of New York, have invented a new and useful Improvement in Fruit-Gatherer; and I do hereby declare that the following is a full, clear, and exact description thereof, which will enable those skilled in the art to make and use the same, reference being had to the accompanying drawings, forming a part of this specification, in which—

Figure 1 shows a perspective view of the frame, with the cloth cover removed, and

Figure 2 shows the device complete.

Figures 3, 4, 5, and 6 show the parts disconnected, and in form for packing or storing away.

Similar letters of reference indicate like parts in all the figures.

This invention consists in an improved method of folding the apparatus so that it is much more snug for transportation or for storing away, as hereinafter explained.

The table is constructed in two parts, A, A', and fitted together by dowel-pins in the centre-pieces C in the usual manner. Each segment, B and B', of the hoop is made up of several straight pieces, 1, 2, 3, 4, and 5, fig. 1, which are pivoted to short connecting-pieces or blocks, d, by pivots f. The ends of the hoop are provided with mortises e e for receiving the end e e, fig. 5, of the centre-pieces C. Alternate sections or sides of the hoop have vertical mortises, k, for holding the legs g' in a detachable and adjustable manner. The cloth table or cover is constructed with chutes, and is secured to the frame by hooking or buttoning its edges over pins i in the frame. The legs g' have a series of holes in their upper ends, so that the hoop may be sustained at various heights by means of pins h placed in said holes.

To pack the device, the pins h are withdrawn from the legs g', and the frame lowered to the ground. The cloth, F, is then detached and removed from the frame, and this frees the segments of the hoop from the centre-pieces, so that the tenons e can be withdrawn from the mortises e in the ends of the hoop. Each segment of the hoop and the cloth is then folded, and the various parts of the device are in compact and convenient form, as shown in figs. 3, 4, 5, and 6, so as to require but little room for storage or transportation. The detachable method of using the cloth allows it to be stored away, where it is less liable to be cut by mice, &c., while in disuse. This method of attaching the legs g' also combines adjustability, so the table can be set level on uneven ground, or at various heights, with cheapness of construction, and also allows the legs to be detached readily for packing.

Having thus described my invention, what I claim as new, and desire to secure by Letters Patent, is—

The polygonal hoop B, when constructed in such manner as to fold separately from the cloth table F and centre-pieces C, as shown in fig. 3, as and for the purpose set forth.

The above specification of my invention signed by me, this 26th day of January, 1868.

C. W. GAGE.
